CLAIM

I claim the ornamental design for a flooring panel surface, as shown and described.

DESCRIPTION

FIG. 1 is a perspective view of a flooring panel surface; FIG. 2 is a top view of the flooring panel surface of FIG. 1; FIG. 3 is a front view of the flooring panel surface of FIG. 1;

FIG. 4 is a right side view of the flooring panel surface of FIG. 1; and,

FIG. 5 is a bottom view of the flooring panel surface of FIG. 1.

The broken lines in the figures depict unclaimed portions of a flooring panel surface or flooring panel surface only and form no part of the claimed design.
